[57] **CLAIM**

The ornamental design for a handle for cookware, as shown and described.

DESCRIPTION

FIG. 1 is a right and front perspective view of a handle for cookware showing my new design;
FIG. 2 is a rear elevational view thereof;
FIG. 3 is a left side elevational view thereof;
FIG. 4 is a top plan view thereof;
FIG. 5 is a bottom plan view thereof; and,
FIG. 6 is a perspective view thereof, the broken line showing of a cover is environmental only and forms no part of the claimed design.

FIG. 1**FIG. 2****FIG. 3****FIG. 4****FIG. 5****FIG. 6**
